(57) **CLAIM**

The ornamental design of an arm pad, as shown and described.

DESCRIPTION

FIG. 1 is a top perspective view showing our new arm pad;

FIG. 2 is a right side view thereof;

FIG. 3 is a front side view thereof;

FIG. 4 is a rear view thereof;

FIG. 5 is a top view thereof;

FIG. 6 is a bottom view thereof; and,

FIG. 7 is a rolled-up perspective view thereof.

In the drawings, the broken lines represent stitching.
